UNITED STATES PATENT OFFICE.

ARTHUR S. PLOWMAN, OF NEW YORK, N. Y.

GAS-BURNER.

1,096,389.

Specification of Letters Patent.

Patented May 12, 1914.

Application filed November 6, 1909, Serial No. 526,498. Renewed October 7, 1913. Serial No. 793,961.

To all whom it may concern:

Be it known that I, ARTHUR S. PLOWMAN, a citizen of the United States, residing in the city, county, and State of New York, 5 have invented certain new and useful Improvements in Gas-Burners, of which the following is a specification.

My invention relates to self-igniting gas burners, the kind wherein a pilot light continuously burns and serves to ignite the main jet when the valve is operated to turn on the gas.

The object of the invention is to construct a gas burner in such manner that the piston 15 operating to control the means for opening and closing the main gas conduit will at no time be in contact with the gas, but will be operatable within a separate compartment to control the valve closing means.

I am aware that heretofore gas burners employing a pneumatically operated piston for opening and closing the main gas conduit are known to the art, and have been in practical operation, but not successfully, 20 owing to the fact that the impurities carried by the gas are deposited on the piston, causing it to stick so firmly that the operation of the air pump will not move it. It is impossible to use this form of valve for outdoor lighting in cold weather because the condensation which occurs, will freeze around the piston and prevent it from being operated. To obviate these difficulties I have devised a gas burner in which I preferably 25 use a ball valve seated on the intake opening of the main gas conduit, and placing directly over said valve a cylinder having therein a magnetized reciprocating piston. When the piston is in one of its extreme positions the ball is without the influence of said magnetic piston, but when the piston is driven over the path of the ball, pneumatically or otherwise, said ball will come within the influence of the magnetic piston and be moved 30 off its seat and held off as long as the piston remains at the extreme of its other position. By constructing the device in this manner it will be readily noticed that the impurities in the gas cannot be deposited on the piston 45 to prevent its operation, nor will the freezing of the condensation affect it.

With these ends in view I have constructed the hereinafter described invention which will be described in detail and the points

of novelty and merit pointed out in the 55 claims.

In the accompanying drawings: Figure 1 is a central vertical section of my improved gas burner. Fig. 2 is a similar section but at right angles to that of Fig. 1. Figs. 3 and 4 60 are modified forms of the gas burner.

In the practical operation and construction of my invention, 1 is the valve casing having an internally threaded lower portion into which is screwed the supply or 65 bracket pipe 2. Directly over the lower portion 2, is an internally threaded portion 3 to which is attached the ordinary burner 4. This burner may be in the form shown or a mantle, it not being material to the invention 70 involved. Bored transversely through the casing is an opening 7 into which is fitted, in a gas tight manner, a thin pipe 8 made of non-magnetic material. Screwed into the lower portion of the casing is a block 10 75 provided with an opening 11 and a concaved or dished upper surface 12. Resting on the top of this plug 10, directly over the opening 11, and in such manner as to normally close said opening 11, is a ball 15, made of 80 any suitable magnetic metal, preferably steel. The passage of the gas from the supply pipe 2, is through opening 11 in block 10 into the body of the casing, around the pipe 8 and through the opening in the upper 85 portion of the casing into the burner or mantle, as shown in Fig. 2. Sliding freely within the tube 8 is a magnetized piston 20 which is normally, or when the gas is cut off, in the position shown in full lines in 90 Fig. 1, that is, so that the ball 15 is just without the influence of said piston. Secured in one end of the tube 8, in any suitable manner, is a plug 25 having a vent hole 26 therein to relieve the pressure when the piston is moved to the position shown in dotted lines in Fig. 1. The other end of the tube 8 also has a plug 28 secured therein. To this plug is attached an air supply and exhaust tube 30 which leads to any kind or 100 style of the well known devices for compressing and exhausting air. In order to prevent the piston from being jarred or moved from the position it should maintain, I place on one end thereof a spring 33, 105 one end of said spring being fastened to the piston by means of a screw 35 the free end pressing against the wall of the tube. This

spring will produce sufficient friction to hold the piston in the desired position. Secured in the casing 1 and provided with an opening 40 leading directly into the supply 2, 5 below the ball 15, is a pipe 41 which leads up to the top of the burner and supplies the gas for the pilot light in the manner common to this style of burner.

The operation of the device, assuming the 10 parts to be in the position shown in Fig. 1, is as follows: Air is forced through tube 30 into tube 8 against the piston 20 causing said piston to be driven through the tube until it strikes the plug 25. The piston being magnetized, and sliding within and surrounded by non-magnetizable material, will act directly upon the ball 15. When the piston passes through the tube over the ball, it will hold the ball within its magnetic influence and carry said ball off its seat and into the position shown in dotted lines in 15 Fig. 1. In this position the ball will be held as long as the piston remains in the position of Fig. 1, that is, with the gas passage open 20 to the burner. When the air is exhausted from the tube 8 the piston will be drawn back to its first position and the ball, being without the influence of the piston, will roll over the gas inlet 11 in plug or block 10 25 and shut off the supply of gas. The top of the block 10 being concaved the ball will quickly close the opening 11.

By referring to Fig. 2 it will be noticed that the supply of gas is from pipe 2, 30 through the block 10, around pipe 8 and out through the top portion of the casing to the burner 4. By constructing the device in this manner it can be readily seen that at 35 no time does the gas come in contact with the piston, thereby keeping it free from all kinds of smudge or deposits and free from 40 the possibility of freezing, by reason of condensation.

In Fig. 3 a modification is shown wherein 45 the device can be used for inverted burners or mantles. In this form the casing 50 has a vertical bore 51 into which is secured, in a gas tight manner, a cup 52 with its closed end within the casing. Secured within the 50 bore 51 at the bottom, is a plug 53 provided with an opening 54. The top of this plug is concaved in the same manner as the plug or block 10 in Fig. 1 and has resting thereon, directly over and closing the opening 55 54, a ball 55. Located within the cup 52 is a magnetized piston 56 which is normally held in the position shown by friction, in the same manner as piston 20. In the top of the cup is a plug 57 to which is attached an air 60 supply and exhaust pipe 58. On one side of the casing is a gas passage 59 which supplies the burner. A pilot light is used in this burner in the same manner as shown in Fig. 65 2. When air is forced into the cup 52 the piston will be driven down and immediately

draw the ball within its magnetic influence and hold it in the position shown in dotted lines permitting the free flow of gas to the burner. The ball will remain in this suspended position until the piston is withdrawn to its upper position whereupon the ball will drop and shut off the flow of gas. 70

In Fig. 4 a further modification is shown wherein two magnetic pistons 65 and 66 are used. These pistons are contained within 75 cups 67 and 68 in the same manner as the piston 56. In this form the ball 70 is magnetically held by one of the pistons in position to close the gas passage, the other piston when brought into action draws the 80 ball away to free the gas passage. Leading from each of the cups 67 and 68 are air tubes 71 and 72 connected with air cylinders 73 and 74. The pistons of the cylinders are worked simultaneously by the handle 80. 85 It will be noticed that when the handle 80 is pulled out the ball will be released by piston 65 and drawn within the influence of piston 66 said piston pulling the ball away from its seat sufficiently far to permit the free 90 flow of gas.

Claims.

1. In a gas burner, a valve operating within the gas passage to open and close the same, and a pneumatically controlled 95 reciprocating magnet without the gas passage capable of controlling said valve.

2. In a gas burner, a valve operating within the gas passage to open and close the main conduit, and a magnetized piston, 100 pneumatically operated, capable of controlling the said valve.

3. In a gas burner, a ball valve for opening and closing the main conduit, and a magnetized piston capable of asserting its 105 influence on said ball valve to control the same.

4. In a gas burner, a casing having a gas passage therethrough, a valve for opening and closing the same, and a magnetized piston capable of moving across said passage within a chamber not open to said gas passage and capable of asserting its influence on said valve to control the same. 110

5. In a gas burner, a casing having a gas 115 passage therethrough, a valve for opening and closing the same, and a piston adapted to move across said passage within a chamber not open to said gas passage and capable of controlling said valve.

6. In a gas burner, a casing, a ball valve within said casing for opening and closing the gas passage, a cylinder projecting across said passage, and a magnetized reciprocating piston pneumatically operated within 125 said cylinder and capable of moving in a path sufficiently close to the ball valve to control the same.

7. In a gas burner, a casing, a valve within said casing for opening and closing the gas 130

passage, a magnetized reciprocating piston operating within a chamber separate from the gas passage and capable of moving in a path sufficiently close to the valve to control the same.

8. In a gas burner, a casing having a longitudinal passage therethrough, a valve within said passage for opening and closing the same, a tube within said casing to form

a separate chamber, and a magnetized piston within said tube capable of asserting its magnetic influence on said valve to control the same.

ARTHUR S. PLOWMAN.
